C. ANLAUF

WALKING STEPLADDER

Filed March 26, 1923

Patented Sept. 4, 1923.

1,467,245

UNITED STATES PATENT OFFICE.

CARL ANLAUF, OF PIPESTONE, MINNESOTA.

WALKING STEPLADDER.

Application filed March 26, 1923. Serial No. 627,726.

To all whom it may concern:

Be it known that I, CARL ANLAUF, a citizen of the United States, residing at Pipestone, in the county of Pipestone and State 5 of Minnesota, have invented certain new and useful Improvements in Walking Step-ladders; and I do declare the following to be a full, clear, and exact description of the invention, such as will enable others skilled in 10 the art to which it appertains to make and use the same.

My invention has for its object to provide a step ladder adapted to be straddled by the operator and constructed in such a manner 15 that by shifting his weight and properly manipulating his legs, he can cause the ladder to walk in numerous directions, without dismounting. Thus, the ladder is extremely 20 advantageous when sizing, painting or otherwise treating walls and ceilings.

It is a further object of the invention to provide, in a ladder of the character set forth, a novel form of hinge for connecting the upwardly converging sections of the 25 ladder and a new arrangement of stops which limit the outward movement of these ladder sections and prevent them from closing into parallel relation.

With the foregoing in view, the invention 30 resides in the novel subject matter herein-after described and claimed, the description being supplemented by the accompanying drawing.

Figure 1 is a perspective view of a ladder 35 constructed in accordance with my invention.

Figure 2 is a side elevation showing the manner in which the ladder may be made to walk.

Figure 3 is an enlarged perspective view 40 of the upper end of the ladder showing more particularly the construction of the hinge.

Figure 4 is an enlarged side elevation of 45 the upper end illustrating more particularly the stop means which limit the opening and closing movement of the two ladder sections.

In the drawing above briefly described, the numerals 1 designate two ladder sections which converge upwardly and are hinged 50 together at their upper ends. Each of these sections comprises a pair of stiles 2 connected at suitable intervals by steps or rungs 3. The operator straddles the upper ends of the 55 two sections 1 and stands upon one of the steps 3 of one section with one foot, while his other foot rests upon the corresponding

step of the other section, thus equally distributing his weight upon the two ladder sections.

Assuming that the ladder stands in the position shown in Fig. 1 and it is desired to move it sideways without dismounting, the operator will shift his weight onto one of the ladder sections 1 as indicated in Fig. 2 and may use the leg adjacent the other section, for swinging the latter outwardly as shown in dotted lines in this view. Then, by shifting his weight onto the section which has just been moved, and pulling inwardly with his other leg, the section which was 70 previously stationary is moved. By repeating these operations, the ladder may be moved to any desired extent. I may further explain at this point that the upper ends of the two sections are rather loosely hinged 75 together which permits them to be so manipulated as to cause the ladder to walk in a direction parallel with the hinge axis. By providing a ladder which may be moved in these manners at will, it is obvious that it 80 will be very advantageous for treating ceilings and walls, for instance, for sizing or painting them.

I have shown two hinges for connecting the upper ends of the ladder sections 1 and 85 as they are both of the same construction, only one will be described. A metal bar 5 is vertically secured to the stile 2 of one of the ladder sections 1 and is provided with an outwardly offset upper end 6 having an 90 opening 7. Another vertical bar 8 is secured to the adjacent stile 2 of the other ladder section 1 and has its upper end reduced and bent to form a horizontal loop or eye 9 which is loosely interlooped with 95 the opening 7. This provides a rather loose hinge connection which permits easy operation of the ladder as above explained. Above the hinge line, the stiles 2 are obliquely cut as indicated at 10 to provide co-acting stops limiting the outward movement 100 of the ladder sections 1, while below the hinge line, said stiles are obliquely cut at a different angle as indicated at 11, thereby providing additional stops which prevent 105 the ladder sections 1 from moving inwardly into such close relation to each other as to be dangerous when operating the ladder.

From the foregoing taken in connection with the accompanying drawing, it will be 110 seen that while my invention is simple and inexpensive, it will be highly efficient and

in every way desirable. As excellent results have been obtained from the details disclosed, these details are preferably followed, but within the scope of the invention as claimed, numerous minor changes may be made.

I claim:

1. A walking step ladder adapted to be straddled by the operator, said ladder comprising a pair of sections, each of which includes a pair of stiles with steps extending therebetween, hinges connecting said stiles together at points spaced below their upper ends, the inner edges of the latter being obliquely cut above the hinges to limit the movement of said sections away from each other and also being obliquely cut below the pivot point of the hinges on a different angle to limit the movement of said sections toward each other.
2. A ladder of the type specified comprising a pair of single ladder sections converging toward each other at their upper ends,

and hinges connecting said sections together at a point spaced below said upper ends, each of said hinges consisting of a metal bar secured vertically to one stile and having an outwardly offset upper end formed with an opening, and a second bar secured vertically to the adjacent stile and having its upper end reduced and bent to form a horizontal eye loosely interlooped with said opening.

3. A structure as specified in claim 1; each of said hinges consisting of a metal bar secured vertically to one stile and having an outwardly offset upper end formed with an opening, and a second bar secured vertically to the adjacent stile and having its upper end reduced and bent to form a horizontal eye loosely interlooped with said opening.

In testimony whereof I have hereunto affixed my signature.

CARL ANLAUF.
